United States Patent Office

Des. 179,342

Patented Dec. 4, 1956

179,342

TELEPHONE TRAY

Leo Flicht, Skokie, Ill., assignor to M and M Corporation, Skokie, Ill., a corporation of Illinois

Application April 25, 1956, Serial No. 41,198

Term of patent 14 years

(Cl. D26—14)

Fig. 1

Fig. 2.

Fig. 3.

I claim:

The ornamental design for a telephone tray, substantially as shown.
